Patented Oct. 19, 1976

241,982

ADAPTER FOR COMPRESSING HUMAN BODY ORGANS FOR X-RAY TREATMENT OR THE LIKE

David T. Evans, Manhattan Beach, Ellen M. Proctor,
Pasadena, Frank R. Brion, Arcadia, and Theodorus M.
Ceelen, La Verne, Calif., assignors to Xerox Corpora-
tion, Stamford, Conn.

Filed Apr. 14, 1975, Ser. No. 567,782

Term of patent 14 years

Int. Cl. D24—99

U.S. Cl. D83—1 H

FIG. 1

FIG. 2

FIG. 3

FIG. 4

FIG. 5

FIG. 6

FIG. 1 is a perspective view of an adapter for compressing human body organs for X-ray treatment or the like.

FIG. 2 is a right side elevation view thereof.

FIG. 3 is a rear elevational view thereof.

FIG. 4 is a left side elevational view thereof.

FIG. 5 is a front elevational view thereof.

FIG. 6 is a top plan view thereof.

We claim:

The ornamental design for an adapter for compressing human body organs for X-ray treatment or the like, as shown and described.
